UNITED STATES PATENT OFFICE.

JOSEPH TAYLOR AND WILLIAM TAYLOR, OF ROWLAND, NEVADA.

SHEEP HOOK OR CATCHER.

1,112,867.

Specification of Letters Patent.

Patented Oct. 6, 1914.

Application filed April 14, 1914. Serial No. 831,768.

To all whom it may concern:

Be it known that we, JOSEPH TAYLOR and WILLIAM TAYLOR, citizens of the United States, residing at Rowland, in the county of Elko, State of Nevada, have invented certain new and useful Improvements in Sheep Hooks or Catchers; and we do hereby declare the following to be a full, clear, and exact description of the invention, such as will enable others skilled in the art to which it appertains to make and use the same.

This invention relates to sheep hooks or catchers of that general class having a pair of spring pressed jaws held open by a trigger, the trigger being tripped by engagement with the leg of a sheep whereupon the jaws automatically grasp and securely hold the leg.

An object of the present invention is to provide a tool of this character having pivoted jaws, the trigger being equipped with a spring which holds the trigger in operative position when the jaws are open, the trigger further being equipped with terminal spaced projections, one of which bears against the jaws for holding the same open, and the other of which performs the function of stops which are adapted to engage with the jaws and prevent the trigger from being disengaged entirely from the jaws upon opening of the same, while at the same time performing the additional function of limiting opening movement of the jaws.

With these and other objects in view, this invention resides in the novel features of construction, formation, combination and arrangement of parts to be hereinafter more fully described, claimed and illustrated in the accompanying drawing, in which:—

40 Figure 1 is a side elevation of the device with the jaws in open position. Fig. 2 is a side elevation of the device with the jaws closed. Fig. 3 is a cross sectional view taken on line 3—3 of Fig. 1. Fig. 4 is a sectional view on line 4—4 of Fig. 1.

Referring to the drawing, the numeral 1 designates a ferrule which is engaged by one end of the handle 2, which may be of any desired length. Pivotaly connected to the ferrule 1 are forwardly and outwardly bowed jaws 3, one of said jaws being provided at its extremity with a lug 4 which is adapted to coöperate with the resilient catch 5 mounted upon the adjacent jaw so that when the lug is engaged by the catch the jaws will be held in their locked position.

The extremities of the jaws 3 are further provided with recesses and sockets 6 and 7 which coöperate with the pin and extension 8 and 9 carried by the extremity of the adjacent jaw, thus when the extremities of the jaws are in contacting relation, the same will be firmly held together. The jaws 3 are provided with slots 10 which are engaged by the trigger bar 11, which is formed from sections 12, each section being provided with heads 13, and spaced inner and outer shoulders 14 and 15. The heads 13 are of such size that when the jaws are in their spread or open positions the heads will rest against the outer surfaces of the jaws 3 while the inner shoulders 14 will be spaced from the inner surfaces of the jaws, and at which time the outer shoulders will engage the inner surfaces of the jaws, thus holding the jaws open.

Having one end engaged with the outer end of the ferrule 1 is a coil spring 16, the other end of which is engaged with the trigger bar 11 which exerts an outward pressure thereupon so that the outer shoulders will engage the jaws so as to hold the same open, but when the trigger bar is moved inwardly the outer shoulders will disengage the jaws, thus permitting the jaws to close.

The inner surfaces of the jaws are provided with webs 17 which have curved edges 18 which are preferably covered with a suitable packing 19 so that when the jaws close and the animal's leg is engaged between the curved edges of the flanges, bruising of the leg is prevented.

The outer surfaces of the jaws are provided with sockets 20 which are engaged by the forward ends of the bowed leaf springs 21, the rear ends of which being fixed to the ferrule 1, said springs serving to close the jaws after the trigger bar has been moved inwardly so that the outer shoulders 15 disengage the jaws.

45 The trigger bar 11 is provided with a rubber buffer 22 which is adapted to engage the leg of the animal when the tool is moved forwardly, thus actuating the trigger bar so that the jaws may spring together and grip the leg of the animal between the curved edges of the flanges 17.

In operation the jaws 3 are spread so that the outer shoulders 15 engage the same, thus holding the jaws in their open position, it being obvious that the spring 16 will hold the trigger bar so as to prevent the jaws

from closing accidentally. Further it will be noted that when the tool is moved forwardly and the leg of the animal engages the buffer 22 the trigger bar will be shifted, thus permitting the jaws to close around the leg of the animal, and simultaneous therewith the catch 5 will engage the lug 4 and hold the jaws firmly locked.

What is claimed is:

1. A tool of the class described comprising a pair of pivotally mounted jaws, a spring pressed trigger bar engaged with the jaws for holding the same open, flanges formed upon the jaws for engaging the animal's leg therebetween after the trigger bar has been shifted by contact with the animal's leg, and means carried by the extremities of the jaws for locking engagement, as and for the purpose set forth.
2. A tool of the class described comprising a ferrule, a pair of jaws pivotally connected to the ferrule, leaf springs having one of

their ends connected to the ferrule and their other ends engaging the jaws, said jaws having slots formed therein; a trigger bar having its ends slidably engaged in the slots, inner and outer spaced shoulders carried by the trigger bar, the outer shoulders being adapted to engage the jaws to hold the same open, flanges carried by the jaws, said flanges having curved edges for engaging around the animal's leg, a buffer carried by the trigger bar which when engaged by the animal's leg shifts the trigger bar to disengage the outer shoulders from the jaws, whereby said jaws automatically close.

In testimony whereof we affix our signatures, in presence of two witnesses.

JOSEPH TAYLOR,
WILLIAM TAYLOR.
